(57) **CLAIM**

The ornamental design for a rotor core plate for an electric motor, as shown and described.

DESCRIPTION

FIG. 1 is a perspective view of a rotor core plate showing our new design;

FIG. 2 is an enlarged view of part of FIG. 1 surrounded by a broken line;

FIG. 3 is a front elevational view of FIG. 1;

FIG. 4 is an enlarged view of part of FIG. 3 surrounded by a two-dash chain line;

FIG. 5 is a rear elevational view of FIG. 1;

FIG. 6 is a left side view of FIG. 1; the right side view being a mirror image thereof;

FIG. 7 is an enlarged view of part of FIG. 6 surrounded by a two-dash chain line;

FIG. 8 is a top plan view of FIG. 1;

FIG. 9 is an enlarged view of part of FIG. 8 surrounded by a two-dash chain line;

FIG. 10 is a bottom plan view of FIG. 1; and,

FIG. 11 is a cross-sectional view of FIG. 3 taken along the 11-11' line.

The evenly spaced broken lines show environment and form no part of the claimed design and the two-dash chain lines depict the extent of the enlarged views and form no part of the claimed design.
